 Motor Products Corporation, Dorchester, Mass.,
 a corporation of Massachusetts

Application September 7, 1938, Serial No. 228,783

8 Claims. (Cl. 201—48)

This invention relates to a control rheostat together with an indicating lamp therefor, and more particularly for use as the control unit for small motors, such as an automobile heater motor.

5 An object of this invention is to produce such a control rheostat with a novel switch structure.

Another object is to provide such an element in which the control resistance is to have substantial heat transfer with the switch element.

10 Another object is to provide a structure in which the control resistance is provided with free circulation of air for cooling the same.

Another object is to provide a protective structure around said resistance to prevent grounding displacement or any distortion of said resistance.

15 Another object is to provide an arrangement in which the indicating lamp is illuminated at its maximum brilliancy for all positions of control.

20 Another object is to provide such a structure incorporating a fuse interposed between the switch and the battery.

A still further object is to provide a novel 25 mounting for the indicating lamp in the foregoing structure.

An additional object is to provide a control device of the above kind for controlling a plurality of operating elements together with the indicating lamp.

30 The foregoing and other objects of my invention will be best understood from the following description of exemplifications thereof, reference being had to the accompanying drawings, wherein:

35 Fig. 1 is a top view of the control unit with the switch and lamp assembly removed therefrom, wherein there is also shown diagrammatically a circuit with which the control unit may be used;

40 Fig. 2 is a back view of the control unit shown in Fig. 1;

Fig. 3 is an end view of the control unit viewed from the bottom of Fig. 2;

45 Fig. 4 is an end view of the control unit together with the switch arm and indicating lamp assembly in place thereon as viewed from the top of Fig. 1;

50 Fig. 5 is a view of the switch arm and lamp socket unit;

Fig. 6 is a bottom view of the unit shown in Fig. 5;

55 Fig. 7 is an enlarged cross-section of the switch arm and lamp assembly taken along line 7—7 of Fig. 8;

Fig. 8 is a top view of the assembled device showing the various positions of control;

Fig. 9 is a view similar to Fig. 1 of another embodiment of my invention;

Fig. 10 is a back view of the control unit shown 5 in Fig. 9;

Fig. 11 is an end view of the control unit viewed from the bottom of Fig. 9;

Fig. 12 is an end view of the control unit together with the switch arm and indicating lamp 10 assembly in place thereon, as viewed from the top of Fig. 9;

Fig. 13 is an enlarged cross-sectional view of the switch arm and lamp assembly taken along the line 13—13 of Fig. 15;

Fig. 14 is a bottom view of the unit shown in Fig. 13;

Fig. 15 is a top view of the assembled modification of Fig. 9 showing the various positions of control;

Fig. 16 is a side view of the casing shown in Fig. 13 with part of the wall broken away to show the internal construction; and

Fig. 17 is a plan view of the detent spring of the switch structure.

In the drawings, 1 represents an insulating body made of ceramic material or other suitable refractory insulation. The body 1 is provided at one end thereof with two square holes 2 extending through said body. In each of the holes 2 is 30 mounted a coil 3 of resistance wire. Due to the fact that the holes 2 are square and the coils 3 are round, sufficient space is left between the walls of the holes 2 and the sides of the coils 3, through which air may freely circulate, thus pro-

35 viding cooling of the coils 3. The two coils 3 are connected in series by means of a loop 4 on the back of the body 1. The loop is secured in place and electrically connected to a conducting pin 5 extending through the insulating body 40

to the front thereof, where it is provided with a contact head 5'. The two outer ends 6—6 of the two coils 3 are connected respectively to two pins 7 and 8 likewise through the insulating body 1.

The coil ends 6—6 thus are securely retained in 45 place on the body 1. The insulating body is recessed to receive the loop 5 and the ends 6.

Also the coils 3 are shorter than the length of the holes 2. In this way the insulating body 1 forms a protective structure around the resistance to 50 prevent any undesired conductive elements from coming into contact with the resistance to ground it or in any other way disturb the electrical connections. The resistance is thus also

55 mechanically protected against displacement or

injuring. The ends of the pins 7 and 8 at the front of the insulating body 1 are provided with contact heads 7' and 8', respectively. A conducting strip 9 at the back of the body 1 is connected to the pin 7 and extends to the side of the body where it supports a binding terminal 10, whereby an external electrical connection may be made. A plate 11 of suitable conducting material is mounted on the front of the insulating body 1, and is retained in place thereon by means of a pin or rivet 12 extending through the body 1. In order to prevent any rotation of the plate 11, tongues 12a formed on the plate 11 extend into corresponding recesses in the body 1.

15 An arcuate contact strip 11a is supported adjacent the upper edge of the plate 11 by two pins 13 and 14 extending through the body 1. The tops of the pins 13 and 14 in the face of the strip 11a are recessed so as to provide detents 20 engaging a corresponding projection on the switch arm 27, to be described below. In order to provide additional positioning detent depressions, the plate 11 is provided with an additional depression 15, and the contact strip 11a with an additional depression 15a. At the back of the body 1, the pin 14 supports a spring clip fuse holder 16. A similar spring clip fuse holder 17 is supported at the bottom of the body 1 by means of a pin 19 extending through projection 25 formed on said body 1. The spring clip 17 is also provided with a binding terminal 20, whereby another external electrical connection may be made to the control unit. A fuse 21, indicated in dotted lines, may be supported at the two ends thereof by the spring clips 16 and 17.

30 The typical circuit shown in Fig. 1 may consist of a battery 22, one terminal thereof being connected to the binding terminal 20 by means of a conductor 23; the other terminal of the battery 22 may be grounded at 24. The element to be controlled by the mechanism may be a motor 25 which may be the heater motor in an automobile, a moving picture projector or the like. One terminal of this motor is connected by means of the conductor 25' to the binding terminal 10, the other terminal of the motor being grounded at 26. The switch arm 27, indicated in dotted lines in Fig. 1, is adapted to overlie the switch plate 11 and the various contacts associated therewith.

35 As will be described in more detail below, an indicating lamp 28 is directly connected to the switch arm 27 through an electrical connection 29. The opposite side of the lamp is grounded at 30.

40 The switch arm 27, which is shown most clearly in Fig. 7, is provided at its central portion with a relatively elongated slot 37 which fits around a sleeve 31. The slot 37 is made elongated to permit a certain amount of rock or play of the switch arm 27, but is shaped to prevent relative rotation between the switch arm and shaft. The rocking is such as to insure at all times a good contact with the switch plate 11 and the various contacts associated therewith. A spring 32 biases the switch arm 27 to the outer end of the sleeve 31, which sleeve is in turn provided with a stop 33 to retain the switch arm in place thereon. The switch arm 27 is bent so as to provide two contact legs 34 and 35 at the opposite ends thereof. One of these legs, for example the leg 35, is provided with a projection 36 which is adapted to fit into the various detent indentations on the contacts 11, as described above. An insulating plate 38 is retained in place on the sleeve 31 by being clamped between a head 39 formed

at the inner end of the sleeve 31 and a clamping shoulder 39a swaged from the sleeve 31 onto the upper face of the plate 38. The sleeve 31 is hollow and receives therein the head 40 of a contact rod 41 extending through the insulating plate 38 and the head 39. In order to bias the contact rod 41 to the outer position, a spring 42 is contained within the hollow sleeve 31.

The insulating plate 38 also carries a lamp socket sleeve 43 which is mounted thereon by means of lugs 44 extending through openings in the insulating plate 38. The sleeve 43 is of the type which retains a lamp thereon by means of bayonet slots cooperating with bayonet pins on the lamp base. The sleeve 43 has these bayonet 15 slots formed therein in a novel manner. At each of four equally-spaced points around the sleeve 43, tongues 45 are cut into the side walls of the sleeve 43 and indented inwardly. Each tongue is provided with an elongated leg 46 and a shorter 20 leg 47 between which is located a recess 48 to receive the bayonet pin 49, mounted on the base 50 of a cooperating lamp 28. The lamp 28 is provided with the usual center contact 52 which directly engages the contact rod 41. Due to the 25 presence of the four equally-spaced long legs 46, the base 50 is accurately centered within the sleeve 43.

The usual lamp 28 is provided with two diametrically-opposed bayonet pins. As will be noted, 30 the socket sleeve 43 is, however, provided with four bayonet slots. By this construction it is unnecessary to orientate the lamp in any particular position in order that it may be inserted in the socket in the proper position. Due to the 35 particular construction described above, it is merely necessary to insert the lamp 28 in any position, whereupon the pins 49 will be guided between the long leg 46 of one tongue and the short leg 47 of the adjacent tongue. Thereupon 40 the lamp can only be rotated in a direction in which the pins 49 will ride over the tops of the two short legs 47 immediately adjacent said pins. Upon releasing the lamp 28, the spring 42 acting upon the contact rod 41 will push the pins 49 45 firmly into position in the recesses 48. Such a construction greatly facilitates the insertion of the lamp in the proper position.

The control unit is also provided with a translucent head 53 formed of glass, plastic, or other 50 translucent material. The head 53 is provided with a thinned portion 54 at the end thereof in order to permit light radiated from the lamp 28 to pass more readily through the head 53 at that point, thus providing a brighter spot at the 55 center of said translucent head. In order to retain the head 53 in position on the structure, the sleeve 43 is provided with an elongated slot 55 at one side in the head thereof. The head 53 is provided with a cooperating elongated tongue 60 or feather 56 on one side of the inner wall thereof. The sleeve 43 on the wall directly opposite said slot 55 is provided with a projection 57 which is adapted to fit into a corresponding depression (not shown) on the inner wall of the head 53. In 65 order to retain the head 53 in place, it is merely necessary to slide it over the sleeve 43 so that the feather 56 slides into the slot 55, whereupon the projection 57 will snap into the corresponding depression in the head 53, thus retaining it in the 70 proper position on the sleeve 43.

A mounting sleeve 58 surrounds the sleeve 43 in such a way that said sleeve 43 freely rotates within the mounting sleeve 58. Non-rotatably carried by the sleeve 58 is a casing 59 which is 75

adapted to cover the switching structure of the control unit. The casing 59 is provided with three tongues 60, each ending with a tab 61. The body 1 is provided with three cooperating recesses 62 in the edges thereof. The casing 59 is inserted on the body 1 so that the tongues 60 fit into the corresponding recesses 62. The tabs 61 are then bent over onto the back face of the body 1, in this way retaining the casing 59 together with the switch arm and lamp socket unit in place on said body 1. As shown in Fig. 8, the casing 59 does not extend along the body 1 to the position at which the coils 3 are located, and thus does not interfere with the circulation of cooling air around said coils 3. In order to provide means for mounting the control unit in place on an automobile, sleeve 58 is threaded externally at 63. A clamping nut 64 (Fig. 4) is received on said threaded portion 63, whereby the control unit may be clamped onto some suitable mounting arm. Such a mounting arm is usually a grounded portion of the automobile frame, and thus the casing of the control element is at ground potential. In order to indicate the various positions of the switch, the head 53 may be provided with an indicating arrow, represented by the solid arrow 66 in Fig. 8.

When the structure described above is connected in the circuit, as shown in Fig. 1, and the head 53 is rotated to the off position, the switch arm 27 will occupy the position indicated by the dotted lines in Fig. 1. In order to prevent rotation of the switch arm 27 beyond this off position in the wrong direction, the plate 11 is provided with an upstanding stop 65. Since the battery is connected to the terminal 20, which in turn is connected through the fuse 21 to the contact 11a through the pin 14, the circuit terminates at this point inasmuch as the switch arm does not engage the contact 11a. Thus, neither the motor 25 nor the lamp 28 is energized. As the head 53 is rotated so as to swing the switch arm 27 in a clockwise position around the pin 12 in Fig. 1, the leg 34 of the switch arm 27 will come into contact with the contact head 7', while the projection 36 will snap into the recess in the contact 11a at the pin 14. Under these conditions, a circuit is completed from the battery through the conductor 23, binding terminal 20, spring clip 17, fuse 21, spring clip 16, pin 14, contact 11a, switch arm 27, contact 7', pin 7, strip 9, binding terminal 10, conductor 25', motor 25, ground 26, and ground 24 back to the battery 22. In this way the motor 25 is connected directly across the battery 22, and therefore operates at its maximum or high speed. It will be noted that the fuse 21 is included in this circuit, and thus protects the motor 25 against overload as well as protecting the switch against accidental short-circuits. A circuit is also established for the lamp 28 which is identical with that established for the motor 25 up to the contact arm 27. However, from there the circuit for the lamp 28 continues through the sleeve 31, the contact rod 41, the lamp terminal 52 through the lamp itself to the base contact 50, the socket sleeve 43 which is grounded, and back through the ground connection 24 to the battery 22. Under these conditions the lamp 28 likewise is connected directly across the battery 22, and is illuminated to its maximum brilliancy. If the switch arm 27 is rotated further in the same direction by means of the head 53, the leg 34 will contact the terminal 5' and the projection 36 on the leg 35 will snap into the depression 15a on the contact 11a.

Under these conditions the circuit remains the same except for the fact that the resistance coil 3 on the right-hand side of Fig. 1 is now connected in the motor circuit previously traced. Due to this series resistance, the motor speed 25 5 will be decreased to its medium value. Since, however, the lamp is still connected directly across the battery 22, its illumination remains unchanged. As the switch arm 27 is rotated further, the leg 34 will come into contact with the contact 8' and the projection 36 will snap into the depression on the contact 11a adjacent the pin 13. Under these conditions, the circuit is altered merely by the interposition of the resistance of both coils 3 in the motor circuit traced above. Under these conditions the additional resistance will slow the speed of the motor down to its low value, but the illumination of the lamp 28 will remain unchanged. It will be noted that further rotation of the switch arm 27 will likewise be prevented by the stop 65. In each of the positions of operation, as indicated above, the projection 36 snaps into a corresponding depression at 13, 14, 15 or 15a. This definitely positions the switch arm 27, and can readily be felt by the operator so that he has no difficulty in locating the switch arm 27 in exactly the proper position. The projection 36 in its corresponding depression likewise prevents shifting of the switch arm 27 from any position in which it is placed, due to vibration or jarring.

Heretofore, in controls of this type, great difficulty has been experienced in damage to the switching structure, due to the heating of the switch structure by the control resistances. I have eliminated this difficulty in my present structure by locating the resistances 3 out of any appreciable heat transfer relation to the switch structure itself, and by providing the air cooling referred to above. This has permitted the utilization of relatively complicated switch structures for accomplishing various types of control, of which the present application is one example. Other types of control which this arrangement makes possible are exemplified in my application entitled Control rheostat switch structure, filed simultaneously herewith.

Another embodiment of my invention is shown in Figs. 9 to 17, inclusive, in which, in addition to a heater motor, a control is afforded for an additional operating element, such as, for example, a defrosting motor within the automobile. In these figures, 101 represents a flat insulating body made of ceramic material, or other suitable refractory insulation. The body 101 is provided at one end thereof with two square holes 102 extending through the body. In each of the holes 102 is mounted a coil 103 of resistance wire. As in the case of Fig. 1, the difference in shape between the holes 102 and the resistance coils 103 affords ample circulation of cooling air around the coils 103. The two coils 103 are connected in series by means of a loop 104 on the back of the body 101. The loop is secured in place and electrically connected to a conducting pin 105 60 extending through the insulating body to the front thereof where it is provided with a contact head 105'. The two outer ends 106-106 of the two coils 103 are connected respectively to two pins 107 and 108 likewise extending through the 70 insulating body. The ends of the pins 107 and 108 at the front of the insulating body are provided with contact heads 107' and 108', respectively. A conducting strip 109 at the front of the body 101 connects the contact 107' to an ad- 75

jacent contact 110' which is mounted upon a pin 110 extending through the body 101 and supporting a binding terminal 111 upon the rear face of said insulating body. By means of the binding terminal 111, an external electrical connection may be made to a battery 120, for example. Adjacent the contacts heretofore described is located a conducting switch plate 112 which is secured on the front face of the insulating body 101 by means of a pin or rivet 113 extending through the body 101 and supporting a binding terminal 114 on the rear face of said insulating body. By means of the binding terminal 114, an external electrical connection may be made 15 from the switch plate to a controlled member, such as, for example, a heater motor 123. In order to prevent the switch plate 112 from being displaced on the body 101, it is provided with a tongue 115 projecting into a recess in the face 20 of the body 101.

In order to provide for the control of an additional operating member, the switch plate 112 is cut away at a predetermined portion 116. In the space left by this cut-away portion is mounted 25 a contact 117 carried by a pin 117 extending through the insulating body 101. The pin 117 supports on the rear face of the body 101 another binding terminal 118 to which an accessory, such as, for example, a defrosting motor 30 126 may be electrically connected. The switch plate 112 may be provided with a plurality of contact positions 119.

A typical circuit, such as shown in Fig. 9, may consist of the battery 120 connected from one 35 terminal thereof by a conductor 121 to the binding terminal 118, and thus to the contact 110'. The other end of the battery 120 may be grounded at 122. The heater motor 123 may be connected from one terminal thereof by the conductor 124 to the binding terminal 114, and thus to the switch plate 112. The motor 123 may likewise be grounded at 125. The accessory motor 128 may be connected from one terminal thereof by a conductor 127 to the binding terminal 118, and 40 thus to the contact 117'. The accessory motor 126 also may be grounded at 128. An indicating lamp 129 is in constant electrical connection 130 with a switch arm 131 which is adapted to overlie switch plate 112 and the various contacts 45 associated therewith, as will be more fully described below. The opposite side of the lamp may be grounded at 132.

The switch arm 131, which is shown most clearly in Fig. 13, consists of two portions, a straight contact arm 133 and an offset contact arm 134. The offset arm 134 is provided with an offset portion 135 which underlies a portion of the arm 133. Both contact arms are slipped over and supported on a conducting sleeve 136. For this 50 purpose the contact arm 133 is provided with a slot 137, and the offset portion 135 of the contact arm 134 is likewise provided with a similar slot. These slots are sufficiently large to provide for a relative rocking motion between the contact arms 55 and the sleeve 136; but are shaped to prevent relative rotation. In order to retain the contact arms on the sleeve 136, a stop member 138 is provided at the outer end of said sleeve. The contact arms are biased to the outer end of the 60 sleeve 136 by means of a compression spring 139. The offset portion 135 is provided with a fulcrum projection 140 which bears against the lower face of the contact arm 133. The contact 134 is provided with a contact portion 141 which is 65 adapted to engage the switch plate 112 at the

contact positions 119 as well as the contact 117. The contact arm 133 is provided on its short end with an auxiliary contact projection 138.

The sleeve 136 carrying the associated switch arm structure is mounted on an insulating plate 5 142 in a manner similar to that described in connection with Fig. 7. Likewise the insulating plate 142 carries a lamp socket sleeve 143. The insulating plate 142 also carries a center contact rod 144 electrically connected to the sleeve 136, 10 and thus to the switch arm unit 131. As above described, the lamp socket sleeve 143 is provided with a plurality of bayonet-recessed tongues 145. The lamp 129 is adapted to be received within the socket sleeve 143 and retained in place thereon by means of the bayonet-recessed tongues 145. This modification is also supplied with a translucent head 146 similar to the head 53 of the previous modification.

Around the socket sleeve 143 is supported a 20 mounting sleeve 147 within which the socket sleeve 143 can turn freely. The mounting sleeve 147 is similar to the mounting sleeve 58 in Fig. 1 and supports a casing 148. The casing 148 is provided with a plurality of tongues 149 which are 25 adapted to fit into corresponding recesses 151 in the body 101. The tongues 149 are also provided with end tabs 150 which are adapted to be bent over upon the rear face of the body 101 to retain the casing and its associated structure in 30 place on said body. In order to provide a positioning mechanism, the edge of the insulating plate 142 is provided with a plurality of detent notches 153. These notches are adapted to co-operate with a resilient detent spring 154 carried 35 by the casing 148. The spring 154 is provided with a projecting central detent portion 155 which is adapted to be received in each of the notches 153 to resiliently retain the switch in a predetermined position of operation. The detent spring 154 is supported in place in the casing 148 by means of two openings 156 formed in the opposite side walls of the casing 148. A tongue 157 on each end of the detent spring 154 snaps into a corresponding opening 156, and thus 40 retains the spring 154 in place. In order to prevent the spring 154 from bending at its detent projection 155, it is provided with two thinned portions 158 on opposite sides of said projection 155. In order to give to the operator an audible 45 click upon the rotation of the switch into a predetermined position, the length of the spring 154 between the two tongues 157 is made slightly shorter than the distance between the inner side walls of the casing 148. Under these conditions 50 such an audible click is produced. In order to provide stops to prevent the rotation of the switch beyond its off position or its low-speed position, the insulating plate 142 is cut away along an edge 159 to provide two shoulders 160 at opposite ends of said cut-away portions. A detent stop 161 is formed in the casing 148 by slotting and indenting the upper side wall thereof. The stop 161 cooperates with the shoulders 160 to limit the rotation of the switch to the proper 55 degree.

When the switch arm is located in the position indicated by the dotted lines in Fig. 9, no contact is made by said switch arm with either the contact 107' or the contact 110', and thus 60 the battery 120 is not connected in the circuit. In this position the elements associated with the control unit are deenergized, and thus this constitutes the off position of the control unit. As the switch arm unit 131 is rotated in a clock- 65 70 75

wise direction, the switch arm 133 comes first into engagement with the contact 110' while the switch arm 134 rides onto the contact 117', the projection 141 snapping into the recess in the face of said contact. Under these conditions the battery 120 is connected through the switch arm unit 131 to the contact 117', and thus energizes the accessory motor 126. The pressure of the contact arm 133 against the contact 117' working through the fulcrum 140 forces the projection 133' of the arm 133 into contact with the underlying portion of the switch plate 112. Thus the motor 123 being connected to the plate 112 is also energized at its maximum speed. It will be noted that due to the fulcrum arrangement, the two contact surfaces of the arm 133 are always forced into simultaneous, good contact with the underlying contact surfaces. The lamp 129 being directly electrically connected to the switch arm unit 131 will be energized to its full brilliancy. As the switch arm unit 131 is shifted clockwise to the next position, the switch arm 133 will engage the contact 107' while the switch arm 134 will engage the switch plate 112, the projection 155 snapping into a corresponding recess 153 on the plate 142. Since the contact 117' is not engaged in this position, the accessory motor 126 is thereupon deenergized and remains deenergized in the subsequent positions of the control unit. However, the heater motor 123 being directly electrically connected to the switch plate 112 is now connected to the battery 121, due to the electrical connection, and established by the switch arm assembly 131. It will be noted that neither of the resistance coils 103 are connected in series with the motor 123, and thus this heater motor will be operated at its maximum or high speed. In the subsequent operations of the switch arm unit, the resistance coils 103 are successively connected in series with the motor 123, substantially as described in connection with Fig. 1, and thus the motor is actuated at its medium and low speed, respectively. However, since the lamp 129 is directly in parallel with the motor 123 in each position of the switch, the intensity of luminosity of the lamp 129 will be decreased in accordance with the decrease in speed of the heater motor 123.

The two-piece construction of the switch arm unit 131 accomplishes other valuable results. Due to the arrangement of the various switch contacts, it is important that each of the contact arms 133 and 134 shall have a good electrical connection with its associated contact in each position of the switch. If but a one-piece switch arm were used, the biasing spring 139 might exert its pressure in connection with one of the contact arms, but the pressure on the other switch arm might be insufficient to establish the desired good electrical connection. Due, however, to the fulcrum relationship afforded by the protection 140 bearing against the switch arm 133 and the relative rocking motions, possible pressure exerted by the spring 139 against the offset portion of the switch arm 135 must necessarily be exerted both upon the switch arm 133 and the switch arm 134. This arrangement, therefore, insures that good electrical contact is made with each of the contacts in each position of the switch arm control unit. Due to the fact that the switch unit is advanced in substantial heat transfer relation with respect to the resistance coils 103, none of the heat energized by said coils 103 can reach the switch structure so as to cause any damage thereto.

Of course it is to be understood that the present invention is not limited to the particular details of construction as described above, as many equivalents will suggest themselves to those skilled in the art. It is accordingly desired that the appended claims be given a broad interpretation commensurate with the scope of the invention within the art.

What is claimed is:

1. A control rheostat comprising a body of refractory insulating material having substantially parallel upper and lower faces, the thickness of said body between said faces being substantially less than the maximum dimension of said faces, an opening extending substantially at right angles to said faces and entirely through said body at a predetermined position thereon, a coil of resistance wire with its axis substantially perpendicular to said faces mounted in said opening, said opening and coil being of such shape as to provide an open space through which cooling air may circulate around said coil through said opening, a plurality of switch contacts mounted on said body on one of said faces displaced substantially from said coil and connected to spaced points on said coil, and a movable switch arm overlying and movable into various contact positions with said contacts, said contacts and switch arm being out of substantial heat transfer relation with respect to said coil.
2. A control rheostat comprising a flat body of refractory insulating material, two openings extending entirely through said body at predetermined positions thereon, a coil of resistance wire mounted in each of said openings, said openings and coils being of such shape as to provide an open space through which cooling air may circulate around said coils through said openings, said coils being connected in series by a conductor electrically connected to a contact pin mounted on said body, the ends of said coils being connected to two additional contact pins also mounted on said body adjacent said first contact pin, a conducting switch plate mounted on said body adjacent said contacts, a movable switch arm adapted to make successive electrical contacts between said switch plate and said contacts, said contacts and switch arm being out of substantial heat transfer relation with respect to said coil.
3. A switch comprising a flat body of refractory insulating material, a plurality of contacts supported on said body, a switch arm assembly adapted to overlie said contacts and to successively connect pairs of said contacts together, an actuating shaft supported adjacent said contacts and carrying said switch arm assembly, said switch arm assembly comprising a pair of contact arms each carried on said actuating shaft, adapted to move along said shaft and perform a limited rocking motion with respect thereto, said two contact arms extending on opposite sides of said shaft, one of said contact arms being provided with an offset portion underlying said other contact arm, said offset portion being provided with a fulcrum projection bearing against the lower face of said other contact arm on the side of said shaft from which said other contact arm projects, and spring means for biasing said contact arms to the outer end of said shaft into engagement with said contacts.
4. A switch comprising a flat body of refractory insulating material, a plurality of contacts supported on said body, a switch arm assembly adapted to overlie said contacts and to successive-

- ly connect pairs of said contacts together, an actuating shaft supported adjacent said contacts and carrying said switch arm assembly, said switch arm assembly comprising a pair of contact arms each carried on said actuating shaft, adapted to move along said shaft and perform a limited rocking motion with respect thereto, said two contact arms extending on opposite sides of said shaft, one of said contact arms being provided with an offset portion underlying said other contact arm, said offset portion being provided with a fulcrum projection bearing against the lower face of said other contact arm on the side of said shaft from which said other contact arm projects, said other contact arm having an auxiliary contact surface projecting on the opposite side of said shaft, said contacts being disposed on said body to provide contact surfaces to be engaged by said contact arms and auxiliary contact surface during each position of said switch, and spring means for biasing said contact arms to the outer end of said shaft into engagement with said contacts.
5. A control rheostat comprising a body of refractory insulating material having substantially parallel upper and lower faces, the thickness of said body between said faces being substantially less than the maximum dimension of said faces, an opening extending substantially at right angles to said faces and entirely through said body at a predetermined position thereon, a coil of resistance wire with its axis substantially perpendicular to said faces mounted in said opening, said opening and coil being of such shape as to provide an open space through which cooling air may circulate around said coil through said opening, a plurality of switch contacts mounted on said body on one of said faces displaced substantially from said coil and connected to spaced points on said coil, and a movable switch arm overlying and movable into various contact positions with said contacts, said contacts and switch arm being out of substantial heat transfer relation with respect to said coil, said insulating body projecting beyond said resistance wire on all sides thereof to prevent accidental touching or displacement of said resistance wire.
6. A control rheostat comprising a body of refractory insulating material having substantially parallel upper and lower faces, the thickness of said body between said faces being substantially less than the maximum dimension of said faces, an opening extending substantially at right angles to said faces and entirely through said body at a predetermined position thereon, a coil of resistance wire with its axis substantially perpendicular to said faces mounted in said opening, said opening and coil being of such shape as to provide an open space through which cooling air may circulate around said coil through said opening, a plurality of switch contacts mounted on said body on one of said faces displaced substantially from said coil and connected to spaced points on said coil, and a movable switch arm overlying and movable into various contact positions with said contacts, said contacts and switch arm being out of substantial heat transfer relation with respect to said coil.

said opening, a plurality of switch contacts mounted on said body on one of said faces displaced substantially from said coil and connected to spaced points on said coil, and a movable switch arm overlying and movable into various contact positions with said contacts, a plate movable with and secured to said switch arm, a plurality of detent depressions in the edge of said plate, and a spring detent mounted on said insulating body and adapted to engage each of said depressions in various positions of operation of said switch arm.

7. A control rheostat comprising a body of refractory insulating material having substantially parallel upper and lower faces, the thickness of said body between said faces being substantially less than the maximum dimension of said faces, an opening extending substantially at right angles to said faces and entirely through said body at a predetermined position thereon, a coil of resistance wire with its axis substantially perpendicular to said faces mounted in said opening, said opening and coil being of such shape as to provide an open space through which cooling air may circulate around said coil through said opening, a plurality of switch contacts mounted on said body on one of said faces displaced substantially from said coil and connected to spaced points on said coil, and a movable switch arm overlying and movable into various contact positions with said contacts, a plate movable with and secured to said switch arm, a plurality of detent depressions in the edge of said plate, a spring detent mounted on said insulating body and adapted to engage each of said depressions in various positions of operation of said switch arm, said plate being cut away along one edge to provide a pair of shoulders, and a stop mounted on said insulating plate to engage said shoulders in limiting positions of said switch arm.

8. A control rheostat comprising a body of refractory insulating material having substantially parallel upper and lower faces, the thickness of said body between said faces being substantially less than the maximum dimension of said faces, an opening extending substantially at right angles to said face and entirely through said body at a predetermined position thereon, a coil of resistance wire mounted in said opening, said opening and coil being of such shape as to provide an open space through which cooling air may circulate around said coil through said opening, a plurality of switch contacts mounted on said body on one of said faces displaced substantially from said coil and connected to spaced points on said coil, and a movable switch arm overlying and movable into various contact positions with said contacts, said contacts being out of substantial heat transfer relation with respect to said coil.
